UNITED STATES PATENT OFFICE

2,078,784

ELECTRIC CIRCUIT BREAKER

Raoul Willheim, Berlin-Oberschoneweide, Germany, assignor to General Electric Company, a corporation of New York

Application November 19, 1936, Serial No. 111,733
In Germany April 30, 1936

5 Claims. (Cl. 200—82)

My invention relates to electric circuit breakers and more particularly to means for protecting a circuit breaker in the event that failure of the circuit opening means results in an incomplete 5 circuit opening operation.

In certain types of electric circuit breakers for interrupting large amounts of power, failure of the circuit opening means, particularly in case of pneumatic operating means, may occur during the circuit opening operation with the result that the movable contact structure remains in an intermediate position, or is moved too slowly away from the fixed contact structure. Consequently the arc drawn between the contacts tends 15 to persist and causes more or less damage to the circuit breaker.

In accordance with the present invention, the circuit breaker operating mechanism is arranged so that a force is continually applied to the 20 movable contact structure, tending to move such structure to the closed circuit position. Thus, in the event that there is failure of the circuit opening means before the movable contact structure has reached the fully open circuit position, 25 the breaker is again immediately reclosed so that damage which might be caused by the persisting arc is prevented. The present invention is particularly suitable for circuit breakers actuated by pneumatic operating means, such as gas blast 30 circuit breakers, for example, wherein the source of gas pressure for operating the switch is also the source of the arc interrupting gas blast. In such a case, it will be apparent that failure of the source of pressure would ordinarily result 35 in failure of the breaker.

A principal object of my invention is the provision of an improved circuit breaker of the aforesaid type which functions to reclose the breaker immediately upon failure of the circuit opening 40 means.

My invention will be more fully set forth in the following description referring to the accompanying drawing, and the features of novelty which characterize my invention will be pointed 45 out with particularity in the claims annexed to and forming a part of this specification.

Referring to the drawing, the single figure thereof is an elevational view, partly in section, and partly diagrammatic, of an electric circuit 50 breaker embodying the present invention.

The circuit breaker shown by way of example 55 is of the liquid-break or oil type and comprises a tank 1 containing a suitable insulating and arc extinguishing liquid 2 such as oil, within which

contact structures 3 and 4 respectively. The contact structure is of the double break bridging type, the bridging member at 4 being operated in a manner well known in the art by a lift rod 5, between the open and closed circuit positions. 5 In the lowered position, the bridging or movable contact structure 4 is in the open circuit position, the circuit being closed by elevating the lift rod 5 so that the contacts 4' carried by the bridging member engage coacting fixed contact structures at 3. The lift rod 5 is guided through the cover structure 1' of the circuit breaker, said cover also supporting the lead-in conductor bushings 6 at the lower ends of which the fixed contacts 3 are mounted. 15

The actuating means for effecting the circuit operation is generally indicated at 7, and in the present instance, a pneumatically operated device is shown. The operating device comprises a piston 8, operably connected to the lift rod 5 20 through a lever 9, which is pivoted at 10, and suitably connected at 11 and 12 to the piston and lift rod respectively. The piston 8 operates within a cylinder 13 which is adapted to be in communication with a source of gas pressure, the application of pressure being controlled by a two-way valve 14. In the position shown, the valve is closed and the cylinder 13 is thereby provided 25 with an exhaust port to atmosphere so that reverse movement of the piston 8 during the reclosing operation is not retarded. 30

In normal operation of the circuit breaker, the valve 14 is opened in any suitable manner, such as by a solenoid 15 energized from the conventional current transformer 16 to admit gas under 35 pressure through the pipe 17 to the piston 8. Upward movement of the piston causes opening of the circuit breaker, the breaker being held in such position by a suitable latching means indicated at 18, coacting with the lift rod 5. 40

In the event that the source of pressure fails before the breaker is open, there is provided a spring 19 seated at one end on a fixed abutment 20 and bearing on a collar 21 secured to the lift rod 5 so as to exert a continual bias on the lift rod in the circuit closing direction. The spring 19, however, is designed so that it is readily overcome by the normal operating force for opening the breaker. When, however, this force fails or is inadequate to complete the opening operation in such a manner as to quickly extinguish the arc, the spring 19 is effective immediately to reclose the breaker and to prevent possible damage due to continuing of the arc. 50

In the normal operation of the breaker, the 55

closing operation is performed by the spring 19 in response to release of the latch 18 which ordinarily engages the lift rod 5 when the same reaches its open circuit position.

5 It should be understood that my invention is not limited to specific details of construction and arrangement thereof herein illustrated, and that changes and modifications may occur to one skilled in the art without departing from the 10 spirit of my invention.

What I claim as new and desire to secure by Letters Patent of the United States is:

15 1. An electric circuit breaker comprising relatively movable contact structure, actuating means for effecting circuit opening movement of said contact structure, means holding said contact structure in open circuit position when the opening operation is fully completed, and means biasing said contact structure towards closed 20 circuit position, said means being effective to re-close said contact structure in the event of failure of said actuating means resulting in incomplete or inadequate opening movement.

25 2. An electric circuit breaker comprising relatively movable contact structure, actuating means for biasing said contact structure in the direction of circuit opening movement, means holding said contact structure in open circuit position when the opening operation is fully completed and means biasing said contact structure at all times towards closed circuit position, said first-named biasing means normally overcoming said second biasing means, and said second biasing means being effective immediately to reclose 30 said contact structure in the event of failure of said first named biasing means.

35 3. An electric circuit breaker comprising relatively movable contact structure, actuating means for effecting circuit opening movement of

said contact structure, a latch for holding said contact structure in the open circuit position only when the opening operation is fully completed, and a spring normally biasing said contact structure towards closed circuit position, 5 said actuating means normally overcoming said spring in the opening operation, and said spring being effective immediately to reclose said contact structure upon a failure of said actuating means during an opening operation. 10

4. An electric circuit breaker comprising relatively movable contact structure, pneumatically operated means for effecting a circuit opening movement of said contact structure, latching means for holding said contact structure in open 15 circuit position only when the opening operation is fully completed, and means normally biasing said contact structure towards closed circuit position, said biasing means being effective to close 20 said circuit breaker upon failure of said pneumatic means during a circuit opening operation.

5. An electric circuit breaker comprising fixed and movable contact structure, a piston operatively connected to said movable contact structure, valve means for controlling application of 25 gas under pressure to said piston for causing opening movement of said contact structure, latching means for holding said contact structure in the open circuit position only when the opening 30 operation is fully completed, and a spring normally biasing said movable contact structure towards closed circuit position, said spring being effective to reclose said contact structure in the event of failure of gas pressure at said piston during the opening operation, said valve means 35 providing an exhaust port for the release of back pressure at said piston during said reclosing operation.

RAOUL WILLHEIM.
